UNITED STATES PATENT OFFICE.

HARBERT K. FORBIS, OF COLUMBUS, OHIO.

THILL-COUPING.

SPECIFICATION forming part of Letters Patent No. 315,759, dated April 14, 1885.

Application filed August 6, 1884. (No model.)

To all whom it may concern:

Be it known that I, HARBERT K. FORBIS, a citizen of the United States, residing at Columbus, in the county of Franklin and State of Ohio, have invented certain new and useful Improvements in Combined Thill-Coupling and Anti-Rattler for Vehicles, of which the following is a specification, reference being had therein to the accompanying drawings.

My invention relates to a combined thill-coupling and anti-rattler for vehicles; and it consists, first, in a concaved metallic plate placed beneath the shaft-eye and resting upon a rubber cushion supported by a transverse plate, the several parts being adjusted vertically.

It further consists in ears or projections depending from the clip-ears and made integral therewith or inserted therein, said projections being screw-threaded and passing through openings in a transverse plate supporting the anti-rattler.

It lastly consists in means for securing the shaft-eye-bolt to the clip-ears.

The details of construction and operation of the several parts will be hereinafter more fully set forth in the specification, and pointed out in the accompanying drawings, in which—

Figures 1 and 4 are vertical sections through the axle and clip; Fig. 2, a front elevation of the device, and Fig. 3 a transverse section through the coupling and anti-rattler.

The object of the device is to provide an anti-rattler that can be adjusted to the shaft-eye, so as to give any friction required, and at the same time be adjusted for wear on the metallic friction-plate. Again, in the thill-coupling I desire to dispense with the nut that is generally used to secure the bolt passing through the shaft-eye and clip-ears, and secure said bolt directly to one of the clip-ears.

Referring more particularly to the drawings, the clip B is secured to the axle A in the usual manner. The ears B' B² have depending from them the projections b, let into or made integral with said ears, and which are screw-threaded to receive nuts c. The exterior ear, B', is screw-threaded to receive the threaded bolt E, provided with a square head, e', by means of which it can be removed or inserted with a wrench. The bolt is only threaded a portion of its length near the head,

so as to engage with the threaded ear B', and is cone-pointed to facilitate its insertion. The shaft-eyes n having been secured to the clip-ears by the bolt E, as just explained, the anti-rattler can now be placed in position 60 without using a clamp or jack to force back the rubber packing.

The anti-rattler consists of the metal piece D, concaved on its upper or bearing side, so as to form a seat for the shaft-eye n. The 65 lower side has two flanges, i, which hold the rubber cushion F. A transverse metallic plate, C, having perforations for the passage of the projections b, is placed underneath the cushion F, and is adjusted up or down by means 70 of the nuts e.

It will be observed that by placing the anti-rattler underneath the thill-eye the weight of the thill is taken from the bolt, and there is therefore less wear on the bolt and thill-eye 75 than when the anti-rattler is placed between the thill and axle, as is usually the case.

The plate C can be tightened up, so as to obtain any degree of friction against the eye n, by the metal piece D, and wear upon said 80 piece can be compensated for. As the bolt E is tapped into the ear B', there is no danger of drawing in the ears and binding the thill-eye, so as to cause wear on both, as is the case with the ordinary thill-couplings where 85 a jam-nut is used on the inner end of the bolt. A thill-coupling made in this manner and provided with the adjustable anti-rattler affords a ready means for replacing the said anti-rattlers by simply removing the nuts e. 90

Having thus described my invention, what I claim is—

1. In a thill-coupling, the clip ears B' B², one of which is screw-threaded, as described, and both provided with projections b, in combination with the threaded bolt E, substantially as and for the purpose set forth. 95

2. In a thill-coupling, the combination, with the clip-ears, one of which is screw-threaded, said ears having the projections b, 100 of the pointed bolt E, the metallic piece D, a rubber cushion and transverse supporting-plate C, substantially as described, and for the purpose set forth.

In testimony whereof I affix my signature in 105 presence of two witnesses.

HARBERT K. FORBIS.
